US0D1084349S

(12) **United States Design Patent** (10) **Patent No.:** **US D1,084,349 S**
(45) **Date of Patent:** **** Jul. 15, 2025**

(54) **HEARING AID COMPONENT**

(71) Applicant: **GN Hearing A/S**, Ballerup (DK)

(72) Inventor: **Henrik Hetz Christiansen**,
Copenhagen (DK)

(73) Assignee: **GN Hearing A/S**, Ballerup (DK)

(**) Term: **15 Years**

(21) Appl. No.: **29/840,959**

(22) Filed: **Jun. 2, 2022**

(30) **Foreign Application Priority Data**

(57) **CLAIM**

The ornamental design for hearing aid component as shown and described.

DESCRIPTION

FIG. 1 is a perspective view of a hearing aid component;
FIG. 2 is a back view of the hearing aid component;
FIG. 3 is a front view of the hearing aid component;
FIG. 4 is a left view of the hearing aid component;
FIG. 5 is a top view of the hearing aid component;
FIG. 6 is a bottom view of the hearing aid component; and,
FIG. 7 is a right view of the hearing aid component.
The portions of the hearing aid component shown in broken lines form no part of the claimed design.

1 Claim, 7 Drawing Sheets
